UNITED STATES PATENT OFFICE.

RICHARD BAUMANN, OF STUTTGART, GERMANY.

HARDNESS-TESTING DEVICE.

Application filed June 21, 1921, Serial No. 479,413.

To all whom it may concern:

Be it known that I, RICHARD BAUMANN, a citizen of the German Republic, and a resident of Stuttgart, Germany, have invented 5 a certain new and useful Improved Hardness-Testing Device, of which the following is a specification.

This invention relates to that class of device for testing the hardness of materials in which 10 a weight under spring control is released at a predetermined position and with a predetermined spring pressure so that it strikes a die and therewith forces the test ball into the material to be tested. In order that such 15 an instrument should be satisfactory it is essential in the first place that during the striking movement there shall be practically no action of frictional forces and the hammer should be continuously central and be 20 always released in exactly the same manner. Secondly a predetermined equal amount of work must be done at each stroke, which on release of the hammer should be transmitted to the die, and thirdly strokes of different 25 strength should be obtainable with one and the same apparatus, according to the hardness and dimensions of the material to be tested. Fourthly it is essential that test 30 balls of different size may be inserted or interchanged with other impression producing pieces. Finally, the spring producing the stroke should be so adjustable with respect as to its length and pressure that 35 strokes of the same strength may be obtained.

In accordance with this invention these results are obtained by the particular arrangements hereinafter described for guiding and releasing the weight. The hammer or 40 weight is not externally guided and in fact is guided solely by a central pin or rod along which it slides. The compression of the spring which acts on the hammer or weight and causes it to accelerate at the moment of 45 release is effected by holding the hammer body by means of three cams uniformly arranged around the weight, while compressing the spring by pressing the testing device on the test material and the necessarily sudden 50 release of the weight is effected by the particular form of these cams and of the shoul-

ders on the weight by means of which said weight bears on the cams. As a result blows of different strength may be imparted by forming the guide sleeve of the testing 55 device with openings at different heights for the cams which raise the weight and release it at a predetermined position, or the weight itself is formed with shoulders to bear on the cams at different points or heights or otherwise. 60

A preferred embodiment of the invention is illustrated in the accompanying drawings: Fig. 1 is a vertical section. Fig. 2 shows diagrammatically the openings in the guide 65 sleeve of the device at different heights and positions. Fig. 3 is a view of a weight formed with shoulders.

As shown, 1 denotes the ball which is pressed on the material to be tested and 70 which due to the force of the weight leaves an impression in the material the depth of which impression, if other conditions are alike, depends on the hardness of the material, and thus forms a measure of the hardness of the material. This ball 1 is mounted in the socket 3 which is screwed into the casing 2 of the device, and is held by a die 4 mounted thereover so that it can be interchanged with other members. On the inner 75 wall of the casing two cams 5 formed with blade springs 6 are symmetrically arranged around the circumference. My invention is not restricted by the use of two cams. These cams 5 may project through openings 80 7 in the casing 2 and through corresponding openings 8 or 9 on an external guide sleeve 10 when said corresponding openings 8 or 9 pass by these openings 7. The guide sleeve 10 thus slides on the casing 2. In the intermediate position of this guide sleeve the cams 5 are pressed inwards. A pin or rod 11 is centrally mounted with respect to sleeve 10 and it is secured thereto. This pin or rod serves as a guide for the weight 12 which 85 is otherwise free. A helical spring 13 is adjustably secured in the guide sleeve 10 by means of a head 14. The bottom end 15 of the spring bears on a shoulder on the weight 12 and by raising this weight the 90 spring is compressed according to the amount which the weight is raised. The 95 spring is compressed according to the amount which the weight is raised. The 100

2
weight 12 has a downwardly inclined annular shoulder 16 which on depression of the guide sleeve 10 contacts with the cams 5 so that when the testing device is placed on the work and the sleeve 10 depressed the weight 12 is held by these cams 5 and the spring 13 compressed. When the openings 9 in the guide sleeve pass the openings in the casing 2 the cams 5 pass through these openings the movement being assisted by their inclined portions parallel to the shoulders 16. The weight is thus suddenly released and the spring 13 which has been previously compressed to the desired extent expands downwardly and drives the weight whose movement is not substantially retarded by friction and imparts a blow, corresponding to the compression of the spring, to the die and to the testing ball or the member 20 provided in lieu thereof. As the openings 9 are provided at different lateral positions in the outer guide sleeve 10 the said sleeve can be turned so that one of these openings moves earlier or later into the path of the opening 8, which produces stronger or weaker blows.

After the weight has been released and the blow has been struck, the guide sleeve 10 is moved outwardly with respect to casing 2.

30 Instead of using different openings laterally arranged in the guide sleeve 10 as shown in Fig. 2 shoulders 16 are provided at different heights on the weight itself as shown in Fig. 3. It is then possible to obtain strokes of different strength according to the amount by which the sleeve 10 is moved out of the casing of the testing device. An additional advantage is secured in that in order to move the testing device again into striking position it is not necessary to move the sleeve 10 up with the ball, it being sufficient to withdraw the guide sleeve 10 from the casing 2 independently of the position in the space thereof. Further modifications may be made so long as the arrangement for obtaining blows of different strength is retained. An internally threaded bushing 17 having a shoulder is fitted into the casing 10 and the top of the spring 13 is 45 adjustably clamped between the bushing 17 and the externally threaded head 14. The rod 11 is connected to the head 19 by the nut 19'. The member 19 is kept in position by the externally threaded cap 18.

55 I have described the parts herein by means of reference numbers but I wish to make it clear that wherever I use such numerals, either in the description or in the claims, that I do not wish to be limited to the details of the embodiments herein illustrated.

The operation of my device is as follows:

The apparatus is placed upon the object to be tested, with the ball 1 in contact with the surface of the said object. The casing 10 is 65 then depressed. When the openings 8 pass

by the opening 7, they force the cams 5 inwardly against the resistance of the spring arm 6. Hence before the shoulder 16 of the weight 12 has passed below the tops of the said cams 5, the said cams 5 have been 70 moved so as to hold the weight 12 and prevent the downward movement thereof. The downward movement of the casing 10 while the weight 12 is being held, causes the compression of the spring 13. When the openings 9 register with the openings 7, the spring arms 6, as well as the pressure of the inclined shoulder 16 upon the inclined top of surface of the cams 5, cause these cams 5 to move outwardly with great 75 rapidity, so that they project through the openings 9 and the weight 12 is released. The weight 12 now strikes the die 4 a sharp blow so as to press the ball 1 into the surface of the object which is being 80 tested. Since the spring 13 can be adjustably held by the parts before described, any one of the shoulders 16 of the weight 12 shown in Fig. 3 can be caused to engage with the cams 5 so as to provide blows of 85 greater or less strength.

Having now particularly described the nature of my invention, what I claim as new and desire to secure by Letters Patent of the United States is:

95 1. In an apparatus for testing the hardness of materials a combination of a weight and a spring cooperating therewith, means for moving the said spring so as to compress it, and means for simultaneously holding the weight so as to prevent the movement thereof by the action of the said spring, and means adapted to automatically cause the release of the said weight when compression of the spring is at a predetermined 100 limit.

2. In an apparatus for testing the hardness of materials the combination of the casing 2, a sleeve 10 slidable thereon, the weight 12 and the spring 13 connected to 110 the casing 10, and holding means located in the casing 2 and adapted to hold the weight 12 while the casing 10 is being moved to compress the spring 13 and means adapted to automatically cause the release of the 115 said holding means when the compression of the spring 13 has reached a pre-determined limit.

3. In an apparatus for testing the hardness of materials the combination of casing 120 2 having the openings 7 and the cams 5 mounted so that they are adapted to move laterally with respect to the openings 7, the sleeve 10 having the weight 12 slidably secured thereto and having the spring 13 also 125 secured thereto, the said weight 12 having the shoulder 16 adapted to be engaged by the cams 5, the said casing 10 also having the openings 9 therein.

4. An apparatus according to claim 3 in 130

which the spring 13 is adjustably held in the casing 10.

5. An apparatus according to claim 3 in which the weight 12 has a plurality of shoulders 16.

6. An apparatus according to claim 3 in which the cams 5 are mounted on spring arms 6, the shoulder 16 and the adjacent

surface of the cams 5 being inclined to the said spring arms 6. 10

In testimony whereof I affix my signature in presence of two witnesses.

RICHARD BAUMANN.
